DEVICE OR ATTACHMENT FOR LIFTING BOXES AND THE LIKE

Filed Dec. 20, 1941

Inventor:
WILLIAM E. KORNER,
by: John E. Jackson
His Attorney.

UNITED STATES PATENT OFFICE

2,314,792

DEVICE OR ATTACHMENT FOR LIFTING
BOXES AND THE LIKE

William E. Korner, Gary, Ind., assignor to Carnegie-Illinois Steel Corporation, a corporation of New Jersey

Application December 20, 1941, Serial No. 423,834

11 Claims. (Cl. 214—75)

This invention relates to devices for lifting boxes and the like and, particularly, to an improved box lifting device or attachment designed especially for use with tractors and the like.

In the steel industry, it is the practice to pack sheet material, such as tin plate, stainless steel, and the like, in flat boxes for shipment. Such boxes, when packed, are extremely heavy and difficult to handle. Heretofore, it has been the practice to load such heavy boxes on freight cars and to transport the same from one place to another in the plant by means of an overhead crane, which was dangerous if the boxes were not properly gripped and supported. Oftentimes such boxes were loaded on freight cars for shipment by hand, which was tedious and usually consumed a great amount of time.

In the present invention there is provided a device for lifting such boxes which may be conveniently attached to the lift carriage of a tractor or so designed as to be used with an overhead crane whereby all of the above named disadvantages have been eliminated.

Accordingly, it is the general object of the present invention to provide an improved device or attachment for use with tractors and similar transporting equipment for lifting boxes and the like which is simple and inexpensive in its construction and, at the same time, a box lifting device which is safe and convenient in its use whereby the loading time is reduced to a minimum.

It is another object of the invention to provide an improved device or attachment for lifting boxes and the like which can be used with existing transporting equipment, and a device which can be easily and quickly attached thereto.

It is a further object of this invention to provide an improved device or attachment for lifting boxes and the like which can be quickly and conveniently adjusted so that it can be used for lifting various size boxes.

Various other objects and advantages of this invention will become more apparent during the course of the following specification and will be particularly pointed out in the appended claims.

In the accompanying drawing there is shown, for the purpose of illustration, one embodiment which my invention may assume in practice.

In this drawing:

Figure 1 is a side elevation of the improved box lifting device or attachment of my invention, showing the same incorporated with a tractor;

Figure 2 is a plan view thereof;

Figure 3 is an end view of Figure 1;

Figure 4 is an end view similar to Figure 3, showing my improved box lifting device supporting a box; and

Figure 5 is a perspective view showing one of the hook-like members for supporting the box at the bottom side thereof.

Referring more particularly to the drawing, the improved box lifting device or attachment of my invention comprises a frame member 2 consisting preferably of a longitudinally extending cantilever I-beam member 3. The I-beam member 3 is supported at the inner end thereof preferably by means of an I-beam member 4 extending substantially perpendicular thereto with the ends thereof being welded together as at 5. There is disposed on the inner side of the I-beam member 4, adjacent the top thereof and directly opposite the end of the I-beam member 3, preferably a plate-like member 6 having holes 7 arranged therethrough to either side of the beam 4. On the lower end of the I-beam member 4 there is arranged, preferably, a pair of inwardly extending plate-like members 8 with one disposed on each side of the beam 4. The plate-like members 8 preferably have aligned holes 9 arranged therethrough for the purpose of receiving a bolt or tractor rod 10 carried by the lifting carriage 12 of the tractor to which the device or attachment of my invention is adapted to be connected. The holes 7 arranged in the plate-like member 6 at the top of the device are for the purpose of receiving bolts 13 for securely attaching the top portion of the frame member 2 to the lifting carriage 12.

On top of the I-beam member 3 there is positioned preferably an I-beam or structural member 14 which is arranged substantially vertically to the I-beam member 3 and there is preferably arranged on the inner side thereof a triangular-shaped plate-like member 15 for reenforcing the same. On the top end of the beam member 14 there is securely disposed preferably a sleeve-like member 16 through which a longitudinally extending adjusting bolt or rod 17 extends having a nut 18 arranged on the inner end thereof beyond the sleeve-like member 16. The outer end of the bolt or rod 17 is connected to the outer end of the I-beam member 3 as at 19 for the purpose of aiding in the support of the same.

On one side of the I-beam member 3 there is arranged preferably a pair of spaced apart downwardly extending plate-like members 20 which are securely welded to the side of the beam. On the opposite side of the beam 3 there is disposed a pair of spaced apart downwardly extending

members, preferably in the form of chains 21. On the same side of the beam, and at the top thereof, there is arranged preferably a pair of spaced apart plate-like lugs 22 having a vertically arranged open-ended slot 23 disposed therein. The width of the slots 23 is slightly greater than the thickness of the links of the chains 21 with any one of the links adapted to be disposed within the slot so that the chains are securely held and supported thereby in a well known manner. On the lower ends of each of the chains 21 there is disposed a hook-like member 24 preferably having a handle portion 25 arranged therewith. The hook-like members 24 preferably have a flange or are notched on the end thereof as at 26 so as to prevent the hook-like members from slipping from position in under the box to be lifted. It will be understood that the frame member is preferably of a welded construction, that is, all the parts are welded together to form the frame.

The device of my invention is used in the following manner. The frame member is first attached to the particular piece of equipment with which it is adapted to be used. If the device or attachment is to be used with a tractor, the frame member 2 is bolted to the lifting carriage 12 of the tractor by means of the bolts 10 and 13, as shown in Figure 1 of the drawing. The tractor, together with the box lifting attachment of the present invention, is then moved to position opposite the box to be lifted. The box to be lifted is then turned on edge and the tractor moved forwardly so that the plate-like members 20 lie directly next to the side of the box. The box is then tilted so that the top portion of the box will lie directly next to the plate-like members 20. The chains 21 are then adjusted as to length so as to correspond with the width or height of the box to be lifted by inserting the proper link of each of the chains in the corresponding slot 23 of the lugs 22 so as to provide chains of the proper length. The hook-like members 24 on the lower end of the chains 21 are then positioned under the box on the side opposite that from the plate-like members 20 by means of handles 25 carried thereby. The box is then ready to be lifted and the same is moved upwardly by the upward movement of the frame member 2 by means of the lifting carriage 12 of the tractor. It will thus be seen that the top portion of the box is prevented from moving outwardly in one direction, due to the plate-like members 20, and in the opposite direction, due to the upper portions of the chains 21, and the lower portion of the box is supported by the hook-like members 24 on the lower ends of the chains 21.

Where it is desired to unload or deposit the box in any particular place, the lifting carriage of the tractor is lowered, together with the frame member 2 carried thereby. After the box has been lowered to position on a supporting surface, it will be seen that the hook-like members 24 are free and can be moved out from in under the box by means of the handles 25 arranged therewith.

As a result of my invention, it will be seen that there is provided a box lifting device or attachment which can be safely and conveniently used to transport boxes and the like from one point to another. It will be seen that a heavy box can be easily and quickly loaded or transported from one point to another by two men, that is, one man operating the tractor, and the other man operating the loading device, which is a decided advantage.

It will be understood that the improved box lifting device or attachment of my invention may be used with an overhead crane or other transportation equipment, as well as a tractor, as disclosed herein.

While I have shown and described one specific embodiment of my invention, it will be understood that this embodiment is merely for the purpose of illustration and description and that various other forms may be devised within the scope of my invention, as defined in the appended claims.

I claim:

1. A device of the class described for lifting boxes and the like comprising a frame member, downwardly extending, substantially rigid means carried by said frame member which is stationary relative thereto against which one side of the top portion of the box or article to be lifted is adapted to lie and which is adapted to be disposed to one side of the box or article, means suspended from said frame member which extends a substantial distance below said first mentioned means and which is adapted to be disposed on the side of the box or article opposite that from said first mentioned means at a spaced distance therefrom, and means carried by said last mentioned means which is adapted to extend in under the bottom of the box or article on that side thereof to support the same, said first mentioned means adapted to prevent the box or article from tipping and said second mentioned means adapted to support the same at the bottom thereof.

2. A device of the class described for lifting boxes and the like comprising a frame member, downwardly extending, substantially rigid means carried by said frame member which is stationary relative thereto against which the outer side of the top portion of the box or article to be lifted is adapted to lie and which is adapted to be disposed to one side of the box or article, means suspended from said frame member which extends a substantial distance below said first mentioned means and which is adapted to be disposed on the side of the box or article opposite that from said first mentioned means at a spaced distance therefrom, said last mentioned means being arranged for pivotal movement relative to said frame member and said first mentioned means, and means carried by said last mentioned means which is adapted to extend in under the bottom of the box or article on that side thereof to support the same, said first mentioned means adapted to prevent the box or article from tipping and said second mentioned means adapted to support the same at the bottom thereof.

3. A device of the class described for lifting boxes and the like comprising a frame member, downwardly extending, substantially rigid means carried by said frame member which is stationary relative thereto against which one side of the top portion of the box or article to be lifted is adapted to lie and which is adapted to be disposed to one side of the box or article, means suspended from said frame member which extends a substantial distance below said first mentioned means and which is adapted to be disposed on the side of the box or article opposite that from said first mentioned means at a spaced distance therefrom, a hook-like portion arranged on the lower end of said last mentioned means and which is adapted to extend in under the bottom of the box or article on that side thereof to support the same, said first mentioned means adapted to prevent the box or article from

tipping and said last mentioned means together with said hook-like portion carried thereby adapted to support the same at the bottom thereof.

4. A device of the class described for lifting boxes and the like comprising a frame member, downwardly extending, substantially rigid means carried by said frame member against which one side of the top portion of the box or article to be lifted is adapted to lie with said means adapted to be disposed to one side of the box or article, at least a pair of spaced apart members suspended from said frame member which extend a substantial distance below said downwardly extending means and which is adapted to be disposed on the side of the box or article opposite that from said first mentioned means at a spaced distance therefrom, said suspended members being movable relative to said frame member and said first mentioned means, and a hook-like portion carried by each of said suspended members adjacent the bottom thereof which are adapted to extend in under the box or article to support the same, said downwardly extending means adapted to prevent the box or article from tipping and said suspended members together with said hook-like portion carried thereby adapted to support the same at the bottom thereof.

5. A device of the class described for lifting boxes and the like as defined in claim 4, including means for adjusting the length of each of said suspended members whereby the same may be lengthened or shortened in order to lift various size boxes or articles.

6. A device of the class described for lifting boxes and the like comprising a frame member, downwardly extending, substantially rigid means carried by said frame member against which one side of the top portion of the box or article to be lifted is adapted to lie and which is adapted to be disposed to one side of the box or article, at least a pair of spaced apart flexible members suspended from said frame member which extend a substantial distance below said downwardly extending means and which are adapted to be disposed on the side of the box or article opposite that from said first mentioned means at a spaced distance therefrom, and a hook-like member carried by each of said flexible members adjacent the lower end thereof which is adapted to extend in under the box or article to support the same, said first mentioned means adapted to prevent the box or article from tipping and said second flexible means together with the hook-like member carried thereby adapted to support the same at the bottom thereof.

7. A device of the class described for lifting boxes and the like as defined in claim 6, including means for adjusting the length of each of the suspended flexible members whereby the same may be lengthened or shortened in order to lift various size boxes or articles.

8. A device of the class described for lifting boxes and the like comprising a frame member, at least a pair of spaced apart relatively short, 10 downwardly extending, substantially rigid members arranged on one side of said frame member which are adapted to be disposed to one side of the box or article to be lifted, at least a pair of relatively long members suspended from and arranged on the opposite side of said frame which extend a substantial distance below said first mentioned members and which are adapted to be disposed on the side of the box or article opposite that from said first mentioned members at a 15 spaced distance therefrom, and a hook-like portion arranged on the lower end of each of said suspended members which is adapted to extend in under the bottom of the box or article to support the same, said first mentioned members 20 adapted to prevent the box or article from tipping and said suspended members adapted to support the same at the bottom thereof.

9. A device of the class described for lifting boxes and the like comprising a frame member, 30 at least a pair of spaced apart downwardly extending, substantially rigid members arranged on one side of said frame member which are adapted to be disposed to one side of the box or article to be lifted, at least a pair of flexible 35 members suspended from and arranged on the opposite side of said frame which are adapted to be disposed on the side of the box or article opposite that from said first mentioned members at a spaced distance therefrom, and a hook-like 40 portion arranged on the lower end of each of said flexible members which is adapted to extend in under the bottom of the box or article to support the same, said first mentioned members adapted to prevent the box or article from tipping and 45 said flexible members adapted to support the same at the bottom thereof.

10. A device of the class described for lifting boxes and the like as defined in claim 9 wherein each of the suspended flexible members consists 50 of a chain suspended from the frame.

11. A device of the class described for lifting boxes and the like as defined in claim 9, including means for adjusting the length of the flexible members whereby the same may be lengthened or shortened in order to lift various size 55 boxes or articles.

WILLIAM E. KORNER.
